UNITED STATES PATENT OFFICE

FREDERICK D. KREUDE, OF BROOKLYN, NEW YORK

REINFORCEMENT FOR CONCRETE

Application filed March 9, 1929. Serial No. 345,662.

The invention relates to wire clip reinforcements for soffits for concrete construction.

A feature of my present invention is the formation of wire re-enforcements for soffits in clip form, the particular contour of the wire being pre-formed to enable the re-enforcements to be positioned about the I-beams or other structural elements in the nature of a clip.

A further feature of my invention is the provision of form spacer elements on the re-enforcements for setting the locations of the molding boards during the period of pouring the cement, and retained as re-enforcing elements in the molded concrete.

A further feature of my invention is the provision of pre-formed clip elements of the re-enforcements arranged to accommodate varying sizes of I-beams and other structural elements.

In carrying out the above stated various forms of my invention, I employ any suitable metal stock, including flat band, wire of round contour or of relatively small cross-sectional area if contours other than round are employed, and to weld or otherwise connect the individual re-enforcements to a re-enforcement interconnecting wire, usually extending longitudinally of the I-beam or other structural element, thus facilitating the handling and shipment in the transportation of the multiple re-enforcement units to the location of installation and the application of the same to the work as required, the fixed spacing of the re-enforcements insuring uniformity of distribution of the individual re-enforcements about the structural elements and within the molded concrete.

A still further feature of my invention is the employment of re-enforcing elements secured to a re-enforcement interconnecting spacer wire, the elements being disposed in staggered relation to one another, which may be of the pre-formed clip type or require manual bending about the structural element at the stage of installation.

Further features and objects of the invention will be more fully understood from the

following detail description and the accompanying drawings, in which

Fig. 1 is a vertical sectional view through an I-beam illustrative of a structural element, showing the use of a clip type of my re-enforcements, the molding boards and the molded concrete about the I-beam;

Fig. 2 is a top plan view of a multiple re-enforcement unit having the formation shown in Fig. 1;

Fig. 3 is a detail vertical sectional view corresponding to Fig. 1, showing a modification;

Fig. 4 is a detail vertical sectional view corresponding to Fig. 1, and illustrating extensions of the re-enforcement wire for spacing the bottom mold board;

Fig. 5 is an edge view of Fig. 4;

Fig. 6 is an elevation of a further modification of my invention;

Fig. 7 is a perspective view of a multiple unit of staggered re-enforcing elements.

Fig. 8 is a vertical sectional view of a re-enforcement embodying my invention as applied to a channel;

Fig. 9 is a plan view of a multiple re-enforcement having the formation shown in Fig. 8;

Fig. 10 is a modification of a self-adjustable re-enforcement of the clip type;

Fig. 11 is a modification of Fig. 10, and

Fig. 12 is a further modification of my invention.

Referring to Fig. 1, the I-beam 10 is represented of conventional shape embodying the lower flange 11, upper flange 12 and intermediate web 13 of desired shapes and dimensions. The molding boards 15 including the bottom molding board 15a are located to mold the concrete 16 of the desired ultimate contour.

My improved re-enforcements, shown formed of round wire stock, comprises the body portion 17 and clip end portions 18, 19, the body portion 17 including a plurality of body spacer formations 20 co-acting with the clip end portions 18, 19 to enable the same to be resiliently passed about the outer edges of the lower flange 11 of the I-beam or other structural element, and further serving to

space the body portion 17 at a predetermined distance from the I-beam.

Usually, the terminal portions 18a, 19a of the clip ends 18, 19 are flared away from the structural element to facilitate the physical passing of the ends about the lower flange 11 of an I-beam or like portion of other structural element.

Preferably, my re-enforcements are employed in multiple, as illustrated in Fig. 2, secured centrally or at any other suitable location to a re-enforcement interconnecting wire 21 disposed above or below the connected individual re-enforcements, by welding or like procedure or by any suitable connecting means. In most uses, the interconnected re-enforcements are spaced at uniform distances from one another. The number of re-enforcements thus secured to the re-enforcement interconnecting wire 21 is selected as required. Two or more re-enforcement interconnecting wires 21 may be employed.

In Fig. 3 is shown a modification of my invention and like parts are designated by like reference characters; however, the body spacing elements 20 are of substantially circular contour as compared with the arcuate contour illustrated in Fig. 1. Also, the end portions designated 22 in Fig. 3 extend uprightly in contact with the side faces of the lower flange 11 and are bent downwardly toward and into contact with the flange web at the ends 22a.

Preferably, also, my re-enforcement embodies a form spacer element for spacing the mold boards and in this instance, the bottom mold board 15a, as shown in Fig. 4. The general re-enforcement construction including its clip ends as illustrated in Fig. 4 corresponds to Fig. 1 and like parts are designated by like reference characters. However, the form spacers 23 shown as extensions of the wire or other stock of the respective clip end portions 18a, 19a, are bent rearwardly in an appropriate manner as is indicated in Fig. 5. Form spacer extensions may be similarly formed for the other parts of the mold.

In the modification of my invention shown in Fig. 6, but one end 19, shown at the left in Fig. 6, is of pre-formed clip construction, the opposite end 24 being arranged for manual bending of the same about the lower flange of an I-beam or equivalent part of other structural elements. The intermediate body spacers 20 are of any desired contour. Such form of my clip may embody the form spacer extension 23, similarly as in Figs. 4 and 5. This figure also shows the re-enforcement interconnecting wire 21 located above and welded to the respective individual re-enforcements.

In multiple unit form of my invention shown in Fig. 6, the alternate units may have

the clip ends and manually bent ends arranged in alternate.

In the form of my invention illustrated in Fig. 7, the re-enforcement interconnecting wire 21 is welded or otherwise secured to the staggered re-enforcement elements 25, the particular elements being selected as desired, that is to say, whether or not with intermediate resilient body spacer portions 20 and whether or not with the clip end terminal portions 27; or whether or not with the form spacer elements, similarly as above illustrated in Fig. 6 at 23. By providing for such staggered relation for the successive oppositely disposed re-enforcement elements, so the respective wires are located advantageously to enable the workmen to clip the same at the desired locations of re-enforcement when of clipped form or to manually bend the same when of manually bent form. Such construction of my invention enables the multiple units to be readily packed at the location of manufacture and readily handled and installed at the location of use.

In the particular form of my invention illustrated in Fig. 7, the same is formed of the resilient body spacer 20 corresponding to that in Fig. 1, which may be modified to the form illustrated in Fig. 3 or that illustrated in Fig. 6; the terminal portion 27 may be of the self-clipping type.

As is illustrated in Fig. 8, for steel buildings of modern construction, such channels are usually employed in the exposed walls of the building, that is to say, the web 31 of the channel 30 is disposed in substantially vertical position.

In the arrangement of my clip type of re-enforcement, shown in Figs. 8 and 9, the terminal clip 32 coacts with the resilient body spacer 34 in the application of the clip end about the lower flange 35 of the illustrated channel 30. In a similar manner, the re-enforcement 33 may be provided at its opposite end with a similar clip formation for the upper flange 36 of the illustrated channel 30. As illustrated in Fig. 8, the upper end of the re-enforcement 33 is unformed for application about the upper flange 36, and after application of the lower clip 32, the upper terminal portion 37 may be bent manually about the upper flange 36 as is indicated in dot and dash outline at 37a.

Such re-enforcement construction having single or double clip end formations are preferably marketed in the form of multiple units connected at predetermined spaced distances from one another by means of the re-enforcement connecting wire 38, as is illustrated in Fig. 9, either centrally or at any other suitable location on the individual re-enforcements.

My clip illustrated in Fig. 8 also preferably embodies a form spacer extension of the type illustrated at 40, formed for example

by bending back the wire stock upon itself as appears in edge view in Fig. 9.

In Fig. 10 is illustrated another form of my invention, which may be termed a universal type for predetermined ranges of widths of flanges of I-beams or other suitable structural elements. In this form of my invention, the opposing preformed elements 41, 42 have a sliding relationship laterally of one another as by being loosely positioned within a loop 43; such loop 43 may be formed by bending about itself the stock of the wire 44. Such form of my invention may be employed for individual pairs of mutually adjustable elements or the multiple arrangement similar to that of the above stated forms of my invention may be employed, that is to say, the re-enforcement wire 44 may serve as the interconnecting and spacing wire similar to the re-enforcement interconnecting spacing wires 21 and 38 in the preceding figures of the drawings. The form of my invention shown in Fig. 10 lends itself well to the employment of two or more interconnecting wires, as illustrated in principle in Fig. 11, in which specific illustrated embodiment the interconnecting wires 50 are welded or otherwise secured at any suitable locations to the respective re-enforcement and the loops 51 of wire, band or other suitable stock passing freely about the intermediate portions of the individual re-enforcements.

The clip ends 45, 46 may have any suitable form of clip as above described, including the intermediate body spacing bends 47, 47, and co-operating with the terminal clip formations.

In a similar manner, form spacer extensions as by bending back the stock at the terminal portions 45a, 46a, may be employed similar as is illustrated in Figs. 4, 6 and 8.

In Fig. 12 I have described a further modification of laterally adjustable re-enforcing elements 52 similar to corresponding parts of Figs. 1 and 11, however, the interconnection being made manually by bending or twisting the terminal portions 53, 54 about one another, as indicated in dotted lines. Such form of my invention may be employed by using multiple re-enforcing elements connected to one another at predetermined spacing by the re-enforcement connecting wire or wires 55.

As appeared from the various forms of my re-enforcements, the same comprise individual re-enforcements each having its body portion spaced a material distance from the lower flange of an I-beam or other portion of a structural element to which it is applied, the body portion being thus spaced by the herein termed body spacing bends of circular or other arcuate or other bent form, such body spacing bends being disposed to engage the lower flange of an I-beam or other portion of

a structural element at locations intermediate the edges of the same.

It will also be observed that the various embodiments of clip ends form the individual re-enforcements embodying my invention, which are formed to have a substantially rectangular bend of the wire at the respective opposite termini of the body portion of each re-enforcement, from which substantially right angular bend the wire or other stock continues from said substantially right angular bend to abut the opposite outer edges of the lower flange on the I-beam or other portion of a structural element, thus providing for a substantial length of the wire or other stock of each re-enforcement at each of the clip ends in abutment with the structural element. Where the clip form, as appears from Fig. 3, extends above the location of abutment with the lower flange of an I-beam or other portion of a structural element, such upper continuation effects additional re-enforcement for the concrete; such additional re-enforcement for the concrete is further enhanced by the engagement of the termini with the structural element of such upper extensions of the wire or other stock.

It will be further observed that the resiliency of the clip ends pursuant to my invention is provided for by the location of the body spacer bends intermediate the edges of the lower flange of an I-beam or other portion of a structural element and the continuation of the wire or other stock from the body spacing bends to such substantially right angular bend which extends into abutment with the flange of an I-beam or other portion of a structural element after application. Furthermore, the flared termini of the clip ends, pursuant to my invention, either of the converging flared form as illustrated in Fig. 3, or of the diverging forms as illustrated in Figs. 1, 4, 6, 7, 8, 10, 11 and 12, provide for additional re-enforcement for the concrete by reason of the extensions of the wire or stock of such flared formation beyond the locations of abutment of the stock with the structural element.

Whereas, I have described my invention by reference to specific forms thereof, it will be understood that many changes and modifications may be made without departing from the spirit of the invention.

I claim:

1. A re-enforcement for a structural member comprising an element having a body portion, said element further including a pre-formed clip portion connected to said body portion for extending about a flange of the structural member, said element further including a portion fixedly connected to said pre-formed clip portion and serving as a form spacer, said form spacer portion having a length to locate its terminus to engage and positively locate the structural element,

whereby the terminus of said form spacer portion upon molding of the concrete is disposed at the plane of said face of the concrete.

5. 2. As an article of manufacture, a soffit clip comprising a body portion, a pre-formed clip portion doubled upon itself and a pre-formed form spacer portion extending from said doubled pre-formed clip portion, said form spacer portion being connected to said body portion, said form spacer portion having a length to locate its terminus to engage and positively locate the mold board for one face of the concrete molded about the structural element, whereby the terminus of said form spacer portion upon molding of the concrete is disposed at the plane of said face of the concrete.

20. 3. As an article of manufacture, a soffit clip comprising a body portion, a pre-formed clip portion doubled upon itself and a pre-formed form spacer portion, said form spacer portion extending from the terminus of said clip portion, said form spacer portion being connected to said body portion, said form spacer portion having a length to locate its terminus to engage and positively locate the mold board for one face of the concrete molded about the structural element, whereby the terminus of said form spacer portion upon molding of the concrete is disposed at the plane of said face of the concrete.

35. 4. A re-enforcement for a structural member comprising a plurality of elements, each element having a pre-formed doubled clip portion adapted to extend about a flange of the structural member, each element further having a form spacer portion extending from said doubled pre-formed clip portion connected to said body portion and an element extending transversely to said plurality of elements and loosely interconnecting the same, said form spacer portion having a length to locate its terminus to engage and positively locate the structural element, whereby the terminus of said form spacer portion upon molding of the concrete is disposed at the plane of said face of the concrete.

50. 5. A resilient self-clipping re-enforcement for a structural member comprising a body portion of predetermined fixed length, oppositely disposed body bend portions respectively connected to said body portion and arranged to locate said body portion at a spacing from the structural element to which the re-enforcement is applied, said body bend portions being disposed to engage the structural element at locations materially remote from the edges of the structural element, and a pre-formed clip end portion extending about an edge of the structural element, the terminus of said clip end portion being flared to facilitate application about the end of the structural element and to provide a re-enforcing extension.

structural element and to provide a re-enforcing extension.

6. 6. A resilient self-clipping re-enforcement for a structure member comprising a body portion of predetermined fixed length, oppositely disposed body bend portions respectively connected to said body portion and arranged to locate said body portion at a spacing from the structural element to which the re-enforcement is applied, said body bend portions being disposed to engage the structural element at locations materially remote from the edges of the structural element, and pre-formed clip end portions connected respectively to said body bend portions by intermediate substantially right angular bends, the termini of said clip end portions being flared to facilitate application about the end of the structural element and to provide respectively re-enforcing extensions.

7. 7. A resilient self-clipping re-enforcement for a structural member comprising a plurality of elements, each element having a body portion of predetermined fixed length, oppositely disposed body bend portions respectively connected to said body portion and arranged to locate said body portion at a spacing from the structural element to which the re-enforcement is applied, said body bend portions being disposed to engage the structural element at locations materially remote from the edges of the structural element, pre-formed clip end portions extending about an edge of the structural element, the terminus of said clip end portion being flared to facilitate application about the end of the structural element and to provide a re-enforcing extension, and an interconnecting re-enforcement element welded respectively to said elements at locations spaced from the structural member.

8. 8. A resilient self-clipping re-enforcement for a structural member comprising a plurality of elements, each element having a body portion of predetermined fixed length, oppositely disposed body bend portions respectively connected to said body portion and arranged to locate said body portion at a spacing from the structural element to which the re-enforcement is applied, said body bend portions being disposed to engage the structural element at locations materially remote from the edges of the structural element, pre-formed clip end portions connected respectively to said body bend portions by intermediate substantially right angular bends, the termini of said clip end portions being flared to facilitate application about the end of the structural element and to provide respectively re-enforcing extensions, and an interconnecting re-enforcement element welded respectively to said elements at locations spaced from the structural member.

9. 9. A resilient self-clipping re-enforcement

for a structural member comprising a longitudinally extending element, a plurality of elements fixedly connected to said longitudinally extending element at opposite sides thereof and staggered relative to one another, each of said elements comprising a body portion of predetermined fixed length, oppositely disposed body bend portions respectively connected to said body portion and arranged to locate said body portion at a spacing from the structural element to which the re-enforcement is applied, said body bend portions being disposed to engage the structural element at locations materially remote from the edges of the structural element, and a pre-formed clip end portion extending about an edge of the structural element, the terminus of said clip end portion being flared to facilitate application about the end of the structural element and to provide a re-enforcing extension.

10. A resilient self-clipping re-enforcement for a structural member comprising a pre-formed body portion of definite length, oppositely disposed pre-formed body bend portions respectively connected to said body portion and arranged to engage the structural element to which the re-enforcement is applied and thereby locate said body portion at a spacing from the structural element, said re-enforcement further having a pre-formed clip end portion adapted to extend about an edge of the structural element, the terminus of said pre-formed clip end portion being flared to facilitate application about the end of the structural element and to provide a re-enforcing extension.

In testimony whereof I have signed this specification this 6th day of March, 1929.

49 FREDERICK D. KREUDER.
